Attorneys.

UNITED STATES PATENT OFFICE.

RAYMOND J. McJOHN, OF CHICAGO, ILLINOIS.

IRONING BOARD.

Application filed January 10, 1924. Serial No. 695,401.

To all whom it may concern:

Be it known that I, RAYMOND J. McJOHN, a citizen of the United States, residing at Chicago, in the county of Cook and State of Illinois, have invented a new and useful Ironing Board, of which the following is a specification.

This invention relates to ironing boards, and, more particularly to appliances therefor, its object being to provide a means whereby the cord leading from the electric current-outlet to the iron may be kept out of the operator's way.

Another object of the invention is to keep the cord referred to free of the object being ironed as the iron is moved over the same.

A further object of the invention is to provide a device of extreme simplicity and one which is efficient in operation.

With the above objects in view, the invention embodies a novel combination and arrangement of parts to be hereinafter described and claimed, attention being directed to the accompanying drawing, in which

Figure 1 is an elevation of the novel appliance,

Fig. 2 is a plan view; and

Fig. 3 is an enlarged fragmental section of the ironing board showing its application thereto.

Referring specifically to the drawing, 5 denotes a typical ironing board, supported on legs 6. The iron is shown at 7, and the cord leading current to the same at 8. This 35 cord is usually made with a plug 9 at one end for insertion into a handy current outlet, and with a connection 10 for attachment to the iron.

Since leading the cord directly from the 40 current outlet to the iron involves the dragging of a length of slack back and forth over the board with the movement of the iron, and consequent discomfort to the operator and soiling of the garment being ironed, the 45 present appliance has been designed to eliminate the slack referred to and keep the cord free of the work, thus relieving the operator of concern in those respects.

To accomplish the desired results, the cord

8 is not altered but only passed through two 50 longitudinally spaced openings 11 and 12 cut in the board 5 near the large end thereof. That part of the cord leading from the plug 9 is passed down somewhat frictionally through a rubber or composition bushing 13 55 lodged in the opening 11, then dropping to receive a pulley-weight 14. From the latter, the cord rises through the board opening 12, passing over a roller 15, and continues in an 60 elevated plane to meet the iron connection 10. The roller 15 is of the concave type, and is journaled on a pin 16 carried by arms 17 of a bracket 18 secured inside the opening 12 by screws 19 or other means engaging the 65 stock of the board.

With the iron in action, it will be seen that the pulley-weight 14 will draw to the under side of the board any slack that may develop in the cord by backing the iron, keeping the upper part of the cord out of the way of the operator's arm, yet at a sufficient height to clear the garment being ironed. On the forward stroke of the iron, the lower section of the cord will yield upwardly only as much 70 as is needed.

While the appliance is suitable for the purpose in the form shown, it is susceptible of various changes and refinements without occasioning a departure from the scope and spirit of the invention.

I claim:

1. A take-up device for a current-supply cord comprising a board, spaced openings in the latter to receive the cord from opposite sides and cause an intermediate portion of the cord to form a drop, and a pulley-weight hung in the drop and freely movable therein.

2. A take-up device for a current-supply cord comprising a board, spaced openings in the latter to receive the cord from opposite sides and cause an intermediate portion of the cord to form a drop, and a pulley-weight hung in the drop and freely movable therein, one of said board openings frictionally 90 engaging the cord and the other containing a roller to facilitate the passage of the same.

RAYMOND J. McJOHN.
